United States Patent Office.

J. D. PRATT, OF CLEVELAND, OHIO.

Letters Patent No. 96,346, dated November 2, 1869.

IMPROVEMENT IN BED-BOTTOMS.

The Schedule referred to in these Letters Patent and making part of the same.

To all whom it may concern:

Be it known that I, J. D. PRATT, of Cleveland, in the county of Cuyahoga, and State of Ohio, have invented certain new and useful Improvements in Bed-Bottoms; and I do hereby declare that the following is a full and complete description of the same, reference being had to the accompanying drawings, making part of this specification, in which—

Figure 1 is a side view of a section of bed-bottom. Figure 2, an end view.

Like letters of reference refer to like parts in the different views.

The nature of this invention relates to a device whereby the ends of the slats composing a bed-bottom are secured to each other, and, at the same time, contributing to the elasticity of the slats.

In fig. 1—

A B represent a section of a pair of the slats comprising the bed-bottom, which are of the ordinary shape, length, &c.

The ends of the slats are connected to each other by a clamp, B'.

Said clamp is constructed in two sections, C D, which are made to close upon each other, and interlock, as shown in fig. 1.

In said figure, it will be observed that the upper section is formed with a square ring, E, Figure 2, under which the ends of the slats are inserted, as shown in fig. 1.

A nib, indicated by dotted line a, penetrates the slats, and thereby prevents them from working out.

The lower section of the clamp is interlocked with the upper section by a hook, indicated by the dotted lines b, fig. 1.

Said hook engages a pin, c, whereby it is supported, and prevented from becoming detached.

The two sections are further secured, in their connection to each other, by rods F, which pass through the division-line of the two sections, as shown in fig. 1.

It will be obvious, that by the introduction of said rods, no movement of the two sections of the clamp upon each other can take place in direction of the slat. Hence, when the two slats are compressed together

by the weight of the person or persons upon the bed, there can be no yielding or displacement of the clamp from such compression, but the connection will remain permanently strong and durable.

Both ends of the slats are alike secured by a clamp of the above description, thus connecting the two together, forming one section of many composing the bottom of the bed separate and distinct from each other, so that one or more can be removed and replaced without disturbing the rest.

Arranged between the slats is a series of springs, H, which may be more or less in number, as the strength of the slats, or the weight thereon to be borne, may require.

The advantage derived from connecting the slats by this manner of clamp is, that each slat is converted into a lever of the first order, the edge of the clamp, at x, acting as fulcrum, on which the slat rests, and the resistance, the loop or ring, under which the extreme end is confined.

By this means, it will be obvious that all the resiliency of the slats is secured to the bed, as the weight upon it at any point between the two fulcra, though it compresses the slats, cannot throw upward the end outside or beyond the fulcrum. Therefore, as above said, all the strength and spring of the slats are obtained, making the bed-bottom much easier and elastic than the same would be were the extreme ends of the slats not so confined, but allowed to spring upward while depressing the central part. Also, a less number of coiled springs H will be required to be interposed between the slats. Hence the bed-bottom is not only much easier to lie upon, but is of considerable less expense in the manufacture.

What I claim as my invention, and desire to secure by Letters Patent, is—

The combination of the section C, attached to ring or loop E, and having ribs a and pin c, section D having hook b, with the rods F F, all constructed to operate in the manner and for the purpose described.

J. D. PRATT.
